RAG CARPET.

No. 15,290.

Patented Aug. 19, 1884.

UNITED STATES PATENT OFFICE.

HENRY THIELE, OF MILWAUKEE, WISCONSIN.

DESIGN FOR A RAG CARPET.

SPECIFICATION forming part of Design No. 15,290, dated August 19, 1884.

Application filed May 2, 1884. Term of patent 14 years.

To all whom it may concern:

Be it known that I, HENRY THIELE, of Milwaukee, in the county of Milwaukee and State of Wisconsin, have originated and invented a new and ornamental Design for Rag Carpets; and I do hereby declare that the following is a full, clear, and exact description thereof, reference being had to the accompanying photograph, forming a part of this specification.

10 My design relates to that class of carpets denominated "rag carpets;" and it consists in certain peculiarities of ornamentation going to make up a pleasing and effective whole, as indicated by the accompanying photographic fac-simile.

15

In my design I show, first, a series of stripes, A A, in which the warp-threads show in each instance on the same transverse lines the entire width of the stripe, while alternating with these stripes A A are the check-stripes B B, which consist, in effect, of a plurality of independent stripes, b b', themselves arranged alternately, so that the warp-threads in the parts b of the stripe B shall show in different transverse lines from the warp-threads in the parts b' of said stripe B; and, further, the said warp-threads form transverse stripes of individual varying and unequal width, and the several independent checks on the same transverse line are of different diameters one from the other, and irregular in this difference, as shown in the said accompanying photograph.

Having thus described and illustrated my new and original design, what I claim is—

1. In a design for rag carpets, the alternate continuous stripes A, and broken or check stripes B, having transverse lines of varying width, substantially as set forth and shown.

2. In a design for rag carpets, the combination of the continuous stripes A A, alternate check-stripes, B B, the latter consisting of the alternate independent stripes b and b', and the transverse stripes of varying and unequal width, substantially as set forth and shown.

3. In a design for rag carpets, the check-stripes B B, consisting of the alternate independent stripes, b and b', and the transverse stripes of varying and unequal width individually, displaying checks of irregularly different diameters one from the other on the same transverse line, substantially as set forth and shown.

4. The design for rag carpets, consisting of the stripes A and B, substantially as described and shown in the accompanying photograph.

In testimony that I claim the foregoing I have hereunto set my hand, at Milwaukee, in the county of Milwaukee and State of Wisconsin, in the presence of two witnesses.

HENRY THIELE.
